UNITED STATES PATENT OFFICE.

CYRENUS WHEELER, JR., OF AUBURN, NEW YORK.

CLOTHES-WRINGER.

SPECIFICATION forming part of Letters Patent No. 599,431, dated February 22, 1898.

Application filed July 18, 1896. Serial No. 599,688. (No model.)

To all whom it may concern:

Be it known that I, CYRENUS WHEELER, Jr., a citizen of the United States, residing at Auburn, in the county of Cayuga and State of New York, have invented new and useful Improvements in Clothes-Wringers, of which the following is a specification.

My invention relates to improvements in that type of clothes-wringers known as "U-spring" wringers, machines in which the journals of the rolls are supported by such springs and the necessary pressure imparted to the rolls.

In the U-spring type of friction-wringers the pressure of the springs upon the roller-shafts is constant and strong whether the machine is in use or idle. When in use, the severe strain on the rolls tends to loosen the elastic covering from the shafts and when idle the pressure permanently flattens it. The degree of separation of the upper from the lower roll when in use is determined by the thickness of the fabric operated upon, which varies greatly in the same piece or garment. When in use, one end of the rolls may be widely separated and the other end in or nearly in contact, or both ends may be widely separated at the same time. The successful use of gear-wheels in the U-spring type of machine has been very difficult, especially if the gear-wheels were on the ends of the roller-shafts and meshed directly together, as there was a liability of the gears to be thrown out of mesh. With the gears at both ends of the rolls out of mesh at the same time the machine becomes a poor type of friction-wringer, and when one end of the rolls remains in mesh there will be danger of the roller-shafts at that end being thrown out of their bearings in the springs. When thin fabrics are passing between the rolls, the strong pressure of the springs will hold the gears too closely in mesh and cause the machine to run hard. Heavier springs than are in use in this type of machine are desirable.

The object of the invention is to better adapt this type of machine to the use of gear-wheels and heavier springs by limiting the pressure of the springs, so that the gear-wheels will not be forced so deeply in mesh as to cause the machine to operate hard or injure the covering of the rolls when idle; and, fur-

ther, to limit the separation of the rolls, so that the gear-wheels will not be thrown out of mesh or their shafts out of their bearings in 55 the springs or the springs severely strained; and, further, to provide for the wear of the journals of the roller-shafts and their bearings in the springs by making the limiting devices adjustable; and, further, to guard 60 against the displacement of the limiting devices by connecting the tops of the guide-plates, which carry such devices, together by a cross-bar, which will serve also as a hand-piece to steady the machine. I attain these 65 objects by the devices illustrated in the accompanying drawings, in which—

Figure 1 is a front view of the machine, being the view the operator will have when using the machine. Fig. 2 is a view in vertical section of the left-hand end of the machine, on the line *x* *x*, Fig. 1, outside of the U-springs. Fig. 3 is a detached view of one of the guide-plates for the left-hand end of the machine; and Fig. 4 is a vertical sectional view of the 75 right-hand end of the machine, on the line *z* *z*, looking at it from the left-hand end of the machine, the guide-plate being broken away, its outline being shown in dotted lines, so as to show the spring and gear-wheels, with the rolls 80 separated. Fig. 5 is a view of one of the guide-plates with the stop *f* removed to show more clearly the stud *g* and the lug *M*. Fig. 6 is a similar view with the stop *f* and screw *h* in place. Fig. 7 is a vertical sectional view of 85 Fig. 6 on the line *y* *y*.

The same letters indicate like parts in all the figures.

A represents the lower and *B* the upper roll. The shaft *C* of the lower roll has its 90 journal-bearings in the front end of the lower branches of the U-springs *D*, and the journal of the shaft *E* of the upper roll has its bearings in the upper branches of the same springs, which are bent into the required 95 shape to receive the journal. The U-springs *D* are united to the ends of the cross-bar *F*, which is placed under the lower branches of said springs and is fastened firmly to them by the screw-threaded studs *G* and nuts *H* of 100 the tub-clamps *I*, holes being formed in the springs and cross-bar for that purpose. The tub-clamps have in one of their branches thumb-screws *J* to grip them to the tub. (See

Figs. 2 and 4, where the cross-bar is shown in section.) The crank P is connected to the right-hand end of the lower shaft, as shown in Fig. 1.

- 5 With the addition of the ordinary guide-plates to the shafts at each end of the rolls the machine so far described would fairly represent the U-spring type of friction-wringers as usually constructed and in public use.
- 10 The gear-wheels shown in the drawings and making a part of the complete organization will be described farther on.
- 15 The construction of the guide-plates and their application to the other devices of the machine will now be described. They are indicated in the drawings by K and have the usual flanges or ribs L on their front edges, which project inwardly in front of the rolls and serve to keep the clothing within the 20 ends of the rolls. They have openings a and b through them, through which the roller-shafts pass, and holes c in their upper ends to receive the cross-piece d. This cross-piece may be of wood or metal. It serves to hold 25 the guide-plates at right angles to the roller-shafts and parallel to each other and as a handle for the operator to steady the machine and tub to which it is connected instead of being obliged to use the edge of the tub for 30 that purpose. Each guide-plate has an outwardly-projecting lug M, which projects over and rests upon the lower branch of the U-springs a short distance back of the journals of the lower-roller shaft. Above this is an- 35 other lug N, projecting outwardly and under the upper branch of the U-springs, and is provided with a set-screw O, the upper end of which serves as a rest or stop for the upper branches of the U-springs to limit the pres- 40 sure of the springs upon the journals of the upper roll, the bearing-point of the springs being a short distance back of the roller-shaft. For satisfactory work the pressure ap- 45 plied by the springs to rollers ten inches in length and one and three-fourth inches in diameter should not be less than seven hundred pounds, and for longer and larger rolls the pressure should be correspondingly increased. As the pressure from U-springs is 50 constant the gear-wheels will be held so deeply in mesh as to cause the machine to run hard, and flattening and injury to the rolls will result if no provision is made to prevent it. By means of the set-screws the adjustment of 55 the pressure can be readily made. To limit the separation of the rolls and better adapt the machine to a cog-wheel system of gearing, the following devices are applied: The guide-plates K at their lower ends have lugs S, which 60 project back under the cross-bar F and serve to hold the guide-plates in a fixed relation to the springs and rolls. On the outside face of the guide-plates K, above the upper branches of the springs D, stops f are attached by a 65 short projecting stud g and held in place by screw h. The stops f have recessed heads g', that fit the studs g. The lower end of the

stop is made eccentric to the stud g, on which it is free to turn when the screw h is loosened. This device can be set to limit the separation 70 of the rolls to the required extent to prevent the gear-wheels from being thrown out of mesh and the springs being strained.

The gear-wheels Q and R are connected to the roller-shafts in pairs outside of the springs 75 D, the gear-wheels Q being attached to the lower shaft C and the gear-wheels R to the upper shaft E of the upper roll. These gear-wheels mesh directly together, the gears of the lower roll controlling the rotation of the 80 upper roll by means of its connecting-gears. Figs. 1 and 2 show the rolls in contact, and Fig. 4 shows the gear-wheels as they appear when the rolls are separated. These gear-wheels have webs e on their outer faces to 85 strengthen their teeth or cogs. The openings a b in the guide-plates K are elongated vertically and are made slightly wider than the shafts C E. By means of the stops f the separation of the rolls can be so limited as to hold 90 the gear-wheels in working contact and permit the upper roll to rise and fall within the working limit of the cogs. If the journals or their bearings become worn by use and they fail to mesh properly, the stops f and O afford 95 a ready means for the proper adjustment of the gear-wheels.

I am aware that in a different type of machine a metal strap or regulator has been used on roller-shafts to hold the gears in mesh, 100 and I have in U-spring machines, in connection with stops to limit the pressure between the rolls and gears, so arranged the guide-plates in connection with the roller-shafts as to limit the separation of the rolls to the work- 105 ing capacity of the gears, but found that so thin pieces of metal afforded so small a bearing-surface on the shafts that the wear was objectionable and some means of adjustment was necessary.

Having described my improvements in clothes-wringers, what I claim as new, and desire to secure by Letters Patent, is—

1. In combination with the rolls of a clothes-wringer, which are provided with gear-wheels, 115 that mesh together, and U-springs, which are united to a cross-bar, back of said rolls, and have bearing-places for the roller-shafts; the guide-plates, provided with outwardly-projecting lugs, that rest upon the lower 120 branches of said springs, and outwardly-projecting lugs provided with adjustable stops, to limit the pressure of the upper branches of said springs upon the roller-shafts, sub- 125 stantially as, and for the purposes stated.

2. In combination with the rolls of a clothes-wringer, which are provided with gear-wheels that mesh together, and U-springs, which are united to a cross-bar, back of said rolls, and have bearing-places for the roller-shafts; the 130 guide-plates provided with lugs that project back under the cross-bar, and adjustable stops, over the springs, to limit the separation of the rolls, and prevent the gears from

being thrown out of mesh, substantially as, and for the purposes stated.

3. In combination with the rolls of a clothes-wringer, which is provided with U-springs, which are united to a cross-bar, back of the rollers, and gear-wheels for revolving the rolls in unison, the guide-plates, provided with outwardly-projecting lugs, that rest upon the lower branches of said springs, and outwardly-projecting lugs provided with adjustable stops, to limit the pressure of the upper branch of said springs, the backwardly-projecting lugs, projecting under the cross-bar, and the adjustable stops to limit the separation of the rolls, substantially as, and for the purposes stated.

- 10
- 15

4. In combination with the rolls of a clothes-wringer, which is provided with U-springs, which are united to a cross-bar, back of the rolls, the guide-plates provided with lugs, to rest upon the lower branches of said springs, and adjustable stops to limit the pressure of the springs, lugs to project under the cross-bar, and adjustable stops to limit the separation of the rolls, and the cross-piece uniting the tops of said guide-plates, substantially as, and for the purposes stated. 20 25
